CLAIM

The ornamental design for a hybrid VTOL vehicle, as shown and described.

DESCRIPTION

FIG. 1 is a right front perspective view of a hybrid VTOL vehicle showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The structural elements depicted by broken lines have been shown for the purpose of illustrating portions of the hybrid VTOL vehicle that form no part of the claimed design.
